UNITED STATES PATENT OFFICE.

WILLIAM ALEXANDER MCLEAN, OF PINE GROVE, ONTARIO, CANADA.

ATTACHMENT FOR METAL VISES.

Application filed October 6, 1928. Serial No. 310,821.

My invention relates to improvements in attachments for metal vises, and the object of the invention is to provide a supplemental jaw member forming a facing for each member of the metal vise, which will be readily attachable to the opposing faces of the vise so as to prevent the marring of easily injured substances, such as wood or soft metal, and it consists essentially of the arrangement 10 and construction of parts as hereinafter more particularly explained.

Fig. 1 represents a perspective view of a metal jaw showing my facing attachment applied thereto.

15 Figs. 2 and 3 are perspective details of the members of the attachment removed from the vise.

Fig. 4 is a plan view showing the attachments in position upon a vise jaw.

20 In the drawing like characters of reference indicate corresponding parts in each figure.

1 indicates the stationary member of a vise and 2 the movable member provided with the 25 usual opposing faces 1^x and 2^x. 3 and 4 are facing members which are preferably formed of wood and fit against the opposing faces of the jaw members and provided with rib portions 3^x and 4^x fitting beneath the gripping portions of the jaw. 5 and 6 are slide bars slidably secured in guides 7 and 8 secured to the back face of each member 3 and 4.

35 The outer ends of the members 5 and 6 are out-turned at 5^x and 6^x so as to grip the outer faces of the jaws when the bar members 5 and 6 are drawn together.

The central portions of the members 3 and 4 are recessed as indicated at 3° into 40 which recess the inner ends of the members 5 and 6 extend, such members being provided with threaded portions 5° and 6° engaged by a turn buckle 9 fitting within the recess 3°.

45 The turn buckle is provided with suitable peripheral perforations 9^x into which any suitable instrument may be inserted for turning the turn buckle, and thereby carry the inturned portions 5^x and 6^x into and out of gripping position with the opposing faces 50 of the jaws.

10 is a U-member connected by a divided stem formed by members 11 and 12 connected by a turn buckle 13 to a cross rod 15 on which they are pivotally swung.

The cross bars 15 are also divided as indicated in Fig. 4 and connected centrally by a turn buckle 16 located in the recess 4° formed centrally of each of the members 3 and 4.

By this means the link of the U-member 10 may be adjusted to suit the length of the body of the stationary jaw member 1. In order to adjust the member to the width of such body the base of the U is divided as indicated at 10^x and 10°, the divided portions being held in straps 17 and 18, the side portions of the U being connected together by a cross member comprising members 19 and 20 connected together by a turn buckle 21. By this means the width of the 70 U-member may be adjusted, and at the same time the sides of the body 1 gripped by the depending portions 19^x.

The member 4 is provided with a similarly constructed U-member with the exception that the divided side portions connected by a turn buckle are connected together at their rear ends by a bolt 22 on which is supported a roller 23 which is adapted to engage or pass over the rib 24 so forming part of the movable jaw 2 so as to securely hold the member 4 in place. The bolt 22 is a divided bolt the members of which are connected by a turn buckle 22^x secured to the roller by a pin 22° so that by 85 turning the roller the turn buckle is turned to make the required adjustment.

Each member 3 and 4 is provided with a supplemental gripping member 25 made of soft metal which may be removably set in 90 position against the upper portion of the face of each member 3 and 4 by being linked to the plate 26 secured to the back of each member 3 and 4 and connected by an interposed link 27 hingedly secured to the upper 95 edge of the plate 26 and to the upper edge of the gripping members 25.

When it is desired to grip a soft piece of wood such as furniture the gripping members 25 are swung back into the dotted position indicated in Fig. 2 so as to leave the faces 3 and 4 clear for engaging the article to be gripped.

When a soft metal part is desired to be gripped the gripping members 25 may be 105 swung into the engaging position indicated in the drawing.

From this description it will be seen that

I have devised a very simple device which is readily applicable to the jaw member of any metal vise and which will prevent the injury to articles gripped by the vise when they 5 are made of easily injurable material.

What I claim as my invention is:—

1. The combination with the opposing jaw members of a metal vise, of a face member adapted to be applied to each opposing face 10 of the vise, a divided slide bar carried on the rear face of each member provided with out-turned gripping portions adapted to engage each side of the jaw, and a turn buckle threaded on the opposing inner ends of the 15 gripping members for drawing them into the engaged position.
2. The combination with the opposing jaws of a metal vise, of a facing member

detachably secured to each opposing face of the vise, a plate of soft metal extending 20 across the upper portion of such facing member, and a hinged link connection between the upper edge of the soft metal plate and the back of the facing member.

3. The combination with a jaw member 25 of a metal vise, of a face member adapted to be applied to the face of the jaw member, a divided slide bar carried on the rear face of the face member provided with out-turned gripping portions adapted to engage 30 each side of the jaw, and threaded means located between the inner ends of the gripping members for drawing them together into engaged position.

WILLIAM ALEXANDER McLEAN.
